RAZOR

Hyman R. Segal, New York, N. Y.

Application October 9, 1936, Serial No. 104,812

14 Claims.

(Cl. 30—43)

This invention relates to a structurally and functionally improved razor or shearing device of the power driven type.

The advantages of employing a so-called power driven razor are well appreciated. However, the disadvantages of a unit of this character are also well known. More particularly in the hands of the ordinary user it is necessary to repeatedly traverse the surface to be cleaned. This is necessary because the ordinary user cannot manipulate the apparatus with sufficient skill to assure of hair being severed at a point immediately adjacent the surface from which it emanates. In fact, it frequently occurs that even after repeated 10 traversals by the apparatus over the skin surface, a sufficiently "close" shave is not obtained.

Thus, it is an object of the invention to provide a unit of this type which, even in the hands of an unskilled operator, will effect a close severance 20 of hair to produce a satisfactory shave.

Such a severance will be effected without in any sense sacrificing the advantages inherent to an apparatus of this character or without danger of damaging the skin cuticle, or otherwise injuring the skin surface.

A further object of the invention is that of furnishing a power driven razor including relatively few parts, each individually simple and rugged in construction, these parts being capable 30 of ready assembly to furnish a unit which will operate over long periods of time with freedom from difficulties.

An additional object is that of furnishing a razor or shearing apparatus, the parts of which 35 may be adjusted to provide for a "coarse" or "close" shave according to the desires of the operator.

With these and other objects in mind, reference is had to the attached sheets of drawings, illustrating different embodiments of the invention, 40 and in which:

Fig. 1 is a side elevation of a razor head with certain of the parts broken away and shown in section to disclose underlying construction;

Fig. 2 is a transverse sectional view taken along the line 2—2 and in the direction of the arrows in Fig. 1;

Fig. 3 is a view similar to Fig. 2, but showing a slightly different form of construction;

Fig. 4 is a view similar to Fig. 1, but showing a still further form of construction;

Fig. 5 is a transverse sectional view taken along the line 5—5 and in the direction of the arrows in Fig. 4;

Fig. 6 is a view similar to Figs. 1 and 4, but

illustrating a still further form of construction;

Fig. 7 is a view taken along the line 7—7 and in the direction of the arrows in Fig. 6;

Fig. 8 is a view similar to Figs. 2, 3, 5 and 7, but showing an alternative form of construction;

5

Fig. 9 is a partly fragmentary sectional side elevation of a further form of head which may be employed;

Fig. 10 is a transverse sectional view taken along the lines 10—10 and in the direction of the arrows as indicated in Fig. 9;

10

Fig. 11 is a view similar to 10, but showing the parts of the mechanism adjusted to occupy a position different from that illustrated in the preceding views;

15

Fig. 12 is a top plan view of a still further form of head and with certain of the parts broken away to disclose in section underlying construction;

Fig. 13 is a front elevation partly in section of the head as shown in Fig. 12;

20

Fig. 14 is a transverse sectional view taken along the line 14—14 and in the direction of the arrows in Fig. 13, and

25

Fig. 15 is a view similar to Fig. 12 but showing a construction which may be included in the apparatus.

In the several forms of apparatus herewith illustrated, a power drive is employed. To this end the unit may include a handle casing 15 within which a motor (not shown) is housed.

30

This motor may effect relative movements of the shearing elements in any desired manner. For example, as illustrated in Figs. 1 and 14, the motor shaft 16 may extend through the base 17 of the head and mount a crank pin 18 engaging one

35

of the relatively movable cutter elements to drive the same in a manner hereinafter described. As afore brought out, however, it is to be understood that relative movements of the shearing elements may be achieved in any desired manner it being

40

understood, however, that the cutter head is preferably detachable from the handle, although normally secured against movement with respect thereto in any desired manner as, for example, by a set screw 19.

45

Referring primarily to Figs. 1 and 2, it will be noted that the severing mechanism includes a guard or encasing member 20 which is preferably formed from a tube of metal, such tube being

50

slotted and having one of its edges 21 depressed into a plane below that in which its other edge extends. The other edge provides guard teeth 22 presenting adjacent their inner edges shearing zones. Disposed within the guard is a knife

55

body 23 having cutting elements 24 cooperative with the teeth 22. It will be noted that these elements, as well as the teeth, are preferably tapered toward the free edge of the unit, and at such edge extend substantially above the edge 21. If desired, the movements of the blade with respect to the guard or encasing member may be confined to a given path, by, for example, having a pin 25 extending from the inner face 10 of the guard and entering trackway 26 formed in the outer face of the cutter or blade body. Also, in the form under consideration, as well as in succeeding forms, the guard may be perforated to accommodate the shaft 16 and especially the crank pin 18, and the latter may ride within a transversely extending groove 27 formed in the base portion of the blade.

In this manner it will be apparent that as shaft 16 rotates the blade will be reciprocated with respect to the guard. Also, as the unit is moved across a surface to be shaved (to the left as viewed in Fig. 2) it will be apparent that the surface adjacent the edge 21 may be firmly pressed into contact with the skin which will thereupon ride in contact with the teeth 22. However, the stubble or hair will freely enter the space between these teeth and edge portion 21 and be severed at a point very closely adjacent the skin surface.

30 In the form of construction shown in Fig. 3, exactly the same structure is employed as in the preceding view, with the exception that the teeth 22 have their upper surfaces preferably concaved as at 28 so that a minimum thickness 35 of material exists adjacent the shearing zone. Moreover, instead of forming the guard from a single tubular unit, a member may be employed which extends throughout, for example, 270°. This member will have as an integral portion 40 of its body the guard teeth. However, a plate 29 will be secured to this member and supplement the same to extend throughout the major portion of the gap which would otherwise exist. This plate may have a ridge 30 at a point short 45 of the cutting zone and in this manner proper guidance for the unit will exist.

If it is desired to have a non-circular form of head, this may readily be achieved by securing to the base portion 17 thereof a guard including a plate bent to present a base portion 31 from which side walls 32 and 33 extend upwardly. The side wall 32 terminates in an inwardly projecting side portion 34 while the side wall 33 extends upwardly beyond this portion and terminates in a comb or toothed portion 35. Disposed within the guard is a cutter element which has its body shaped to conform to the base and inwardly extending side walls of the guard. This cutter element includes a body 36 and cutting members 37 which lie closely adjacent the teeth 35. In using a unit of this character it is, of course, moved to the right as viewed in Fig. 5, but it will be understood that there is again present the gap which allows for the proper entry 65 of the hair to be severed and guidance of the skin supporting such hair.

In Figs. 6 and 7, the guard includes an encasing member or shell including a base portion 38 from which side walls 39 and 40 extend. The upper edge of the first side wall defines a comb or guard portion 41 extending inwardly and upwardly and the upper edge of wall 40 terminates in an inwardly and downwardly extending portion 42. Again, a proper guiding and receiving 75 gap is presented and it is obvious that within

this shell the cutter body 43 including cutting elements 44 may be disposed. These elements, of course, lie adjacent the guard teeth 41 and the skin will bridge the zone between the teeth 41 and the inwardly extending portion 42, while the hair to be severed will enter the spaces between the teeth 41.

In the form of construction shown in Fig. 8, the guard 45 is constructed similarly to the body of the guard as shown in Fig. 3, and includes 10 teeth 46. However, the plate 29 is dispensed with and the gap extends from the edges of the teeth through to the main edge of the guard body. The cutter body 47 including elements 48 is also similar to that shown in Fig. 3, and in 15 operating the unit it will be apparent that the skin will be stretched or tensioned between the opposed edges of the guard and the hair will readily be severed in passing through the shearing zone.

In Figs. 9, 10 and 11, the head includes a substantially circular guard body 49, having teeth 50 and within which there is disposed a cutter 51 provided with cutting elements 52. In other words, the structure follows substantially that taught in Fig. 8. However, a plate 53 is interposed between the base 17 and the guard body 49 and may be connected thereto by being formed with a slot 54 through which the shank of a bolt 55 extends. Obviously, upon this bolt being loosened, the plate may, within limits, be rotated with respect to the guard, but upon the bolt being tightened the plate will be locked against movement. This plate continues or extends to a point adjacent the cutting zone provided by elements 50—52, and at that point is preferably formed with an inwardly extending portion 56'. The inner end of this portion may be defined by an outwardly bulged zone 56 and it will be obvious, as shown in Fig. 10, that the skin surface 40 may not materially enter the gap even though the unit is firmly pressed against such skin surface. Consequently the hairs will not enter the gap to the same extent as would otherwise be the case. Thus, it follows that a "coarse" shave will 45 result.

However, by simply loosening the bolt or bolts 55, the plate may be swung to, for example, the position of Fig. 11. To facilitate such rotational movement, this member may have a knurled portion 57 to be readily contacted between the fingers of the operator. Under such adjustment it is, of course, apparent that with the use of ordinary pressure the skin will enter the gap to an even greater extent and will contact the teeth 55 50. Thus the hairs will penetrate the apparatus to a greater extent and be sheared at points immediately adjacent the skin surface. Thus, a "close" shave will result.

If it is found that the form of adjustment provided in Figs. 9 and 11 is objected to because it is necessary to remove the head from the handle to effect the adjustment, such objections may be readily overcome by again employing a head as in Figs. 12 to 14 involving a guard and cutter 65 similar to that previously described. Thus, there will be included a guard shell 58 having teeth 59 and which shell is interrupted throughout a considerable portion of its circumference. Disposed within the shell is a cutter 60 having cutting elements 61 cooperative with teeth 59, this cutter again terminating substantially adjacent the points of termination of the shell. A plate 62 formed with an inwardly extending edge 63 may be employed and adjacent which edge a 75

bulged portion 64 may be provided. Adjacent its base the plate is formed with a slot 65 through which the shank of a set screw 66 may extend. This shank may have screw threaded engagement with a socket formed in the base 17. Obviously, with the bolt 66 loosened, the plate may be shifted to close to a greater or lesser extent the gap which would otherwise exist. To facilitate the shifting the plate may have an outwardly struck portion 67 and this plate should, of course, be formed of spring steel stock and possess characteristics such that it will tend constantly to shift outwardly. To restrain the plate from improper movements, the guard may have inwardly extending guiding elements 68 which overlie the edges of the plate. Obviously, incident to this construction, a yielding form of guide is presented which may readily be adjusted to provide exactly the type of shave which is desired.

Finally, referring to Fig. 15, it will be observed that, if desired, that edge of the guard which extends toward the shearing zone, may be formed with teeth 69. As illustrated, these teeth are provided in the edge of the plate but it is of course obvious that they might be provided in the outer edge of any member or surface defining that side of the gap which is opposite from the shearing zone.

From the foregoing it will be appreciated that, among others, the several objects as aforementioned are achieved. It will be obvious that numerous changes in construction and rearrangement of the parts might be resorted to without departing from the spirit of the invention as defined by the claims.

Having described my invention, what I claim as new and desire to secure by Letters Patent is:

1. An apparatus of the character described including a guard presenting a blade receiving space, a blade enclosed within said guard, and said guard presenting materially separated edge portions to provide a hair receiving gap, teeth formed in one of the edge portions of said guard, cutting elements forming a part of said blade and cooperative with said teeth, the other edge of said guard terminating in a plane below that of said toothed edge, and means associated with said guard and extending to a point adjacent said toothed edge to partially close said gap.

2. An apparatus of the character described including a guard presenting a blade receiving space, a blade enclosed within said guard, and said guard presenting materially separated edge portions to provide a hair receiving gap, teeth formed in one of the edge portions of said guard, cutting elements forming a part of said blade and cooperative with said teeth, the other edge of said guard terminating in a plane below that of said toothed edge, and a plate portion secured to said guard and extending toward the toothed edge of the same.

3. An apparatus of the character described including a guard presenting a blade receiving space, a blade enclosed within said guard, and said guard presenting materially separated edge portions to provide a hair receiving gap, teeth formed in one of the edge portions of said guard, cutting elements forming a part of said blade and cooperative with said teeth, the other edge of said guard terminating in a plane below that of said toothed edge, and a plate portion secured to said guard and extending toward the toothed edge of the same and below the plane of such edge.

4. An apparatus of the character described including a guard presenting a blade receiving space, a blade enclosed within said guard, and said guard presenting materially separated edge portions to provide a hair receiving gap, teeth formed in one of the edge portions of said guard, cutting elements forming a part of said blade and cooperative with said teeth, the other edge of said guard terminating in a plane below that of said toothed edge, a plate having an edge extending toward said toothed edge, and means for adjustably supporting said plate with reference to said guard.

5. An apparatus of the character described including a guard presenting a blade receiving space, a blade enclosed within said guard, and said guard presenting materially separated edge portions to provide a hair receiving gap, teeth formed in one of the edge portions of said guard, cutting elements forming a part of said blade and cooperative with said teeth, the other edge of said guard terminating in a plane below that of said toothed edge, a plate having an edge extending toward said toothed edge, and an outwardly extending portion forming a part of said plate and lying adjacent said toothed edge.

6. An apparatus of the character described including a longitudinally slotted guard arcuate in section, teeth formed in one of the longitudinal edges of said guard, a blade enclosed within said guard and movable with respect thereto, cutting elements forming a part of said blade and lying adjacent said teeth, and a plate having one of its edges extending adjacent but spaced from said teeth and elements, said plate being secured adjacent its other edge to said guard.

7. An apparatus of the character described including a guard presenting a plate including base and side portions, the height of one of said side portions being greater than that of the other, teeth formed in the edge of such side portion, a blade disposed within said guard to be movable with respect thereto, and cutting elements forming a part of said blade and disposed adjacent said teeth and spaced from the upper edge of the second side portion of said plate.

8. An apparatus of the character described including a guard presenting a plate including base and side portions, the height of one of said side portions being greater than that of the other, teeth formed in the edge of such side portion, a blade disposed within said guard to be movable with respect thereto, and cutting elements forming a part of said blade and disposed adjacent said teeth and spaced from the upper edge of the second side portion of said plate, said teeth and elements extending inwardly toward said second side portion.

9. An apparatus of the character described including a guard presenting a plate including base and side portions, the height of one of said side portions being greater than that of the other, teeth formed in the edge of such side portion, a blade disposed within said guard to be movable with respect thereto, cutting elements forming a part of said blade and disposed adjacent said teeth and spaced from the upper edge of the second side portion of said plate, said teeth and elements extending inwardly toward said second side portion, and an inwardly extending portion projecting from the upper edge of such shorter side.

10. An apparatus of the character described including a longitudinally slotted guard substantially arcuate in cross section, teeth formed in

one of the longitudinal edges of said guard, a blade, cutting elements forming a part of said blade and cooperative with said teeth, a plate conforming to the contour of said guard and 5 extending from a point beyond the second edge portion thereof toward said toothed edge portion, and means for mounting said plate whereby the latter may be shifted around said guard.

11. An apparatus of the character described 10 including a longitudinally slotted guard substantially arcuate in cross section, teeth formed in one of the longitudinal edges of said guard, a blade, cutting elements forming a part of said blade and cooperative with said teeth, a plate conforming 15 to the contour of said guard and extending from a point beyond the second edge portion thereof toward said toothed edge portion, means for mounting said plate whereby the latter may be shifted around said guard, and means for normally locking said plate against movement with 20 respect to said guard.

12. An apparatus of the character described including a guard presenting a blade receiving space, a blade enclosed within said guard, and 25 said guard presenting materially separated edge portions to provide a hair receiving gap, teeth formed in one of the edge portions of said guard, cutting elements forming a part of said blade and cooperative with said teeth, the other edge of 30 said guard terminating in a plane below that of said toothed edge, a plate portion secured to said guard and extending toward the toothed edge of the same, and teeth formed in the free edge of said plate.

35 13. A razor including a guard presenting a

longitudinally extending bore and a similarly extending slot providing entrance to said bore, and a longitudinally slotted blade reciprocable within said bore, guard teeth forming a part of said guard and extending from one of the slot edges 5 thereof, the opposite edge of said guard presenting a rounded surface for contact with the surface to be shaved, cutting teeth forming a part of such blade and disposed adjacent said guard teeth for cooperation therewith to perform a 10 shearing action, the ends of such teeth and the opposed edges of the blade and guard slots being so arranged that said opposite rounded surface of the guard lies in a curved plane which does not coincide with the plane of said guard teeth. 15

14. A razor including a guard presenting spaced side walls, inwardly extending guard teeth disposed adjacent the upper edge of one of said side walls, the opposite edge of said guard presenting a rounded surface for contact with the surface to be shaved, a blade mounted for reciprocation between said side walls and being formed with a slot of material width, cutting teeth forming a part of said blade and extending from one of the side edges thereof, said blade teeth being disposed adjacent said guard teeth to cooperate therewith in performing a shearing operation, and said teeth being related to the second side wall of the guard and spaced therefrom to an extent such that a slot is furnished through which the surface to be shaved may enter said guard and said opposite rounded surface of the guard lying in a 20 curved plane which does not coincide with the plane of said guard teeth. 25

HYMAN R. SEGAL. 30 35
